UNITED STATES PATENT OFFICE

147,777

DESIGN FOR A BOTTOM FOR BOWLING BALL BAGS OR THE LIKE

Angus D. Bain, Glen Ellyn, Ill., assignor to The Brunswick-Balke-Collender Company, Chicago,
Ill., a corporation of Delaware

Application January 31, 1946, Serial No. 126,133

Term of patent 14 years

(Cl. D34—5)

To all whom it may concern:

Be it known that I, Angus D. Bain, a citizen of the United States, residing in Glen Ellyn, in the county of Du Page and State of Illinois, have invented a new, original, and ornamental Design for a Bottom for Bowling Ball Bags or the like, of which the following is a specification, reference being had to the accompanying drawings, forming a part thereof.

Fig. 1 is a top plan view of a bottom for a bowling ball bag or the like, showing my new design;

Fig. 2 is a sectional view along the line 2—2 of Fig. 1;

Fig. 3 is a bottom view thereof;

Fig. 4 is an elevational view looking at the bottom edge of Fig. 1.

I claim:

The ornamental design for a bottom for bowling ball bags or the like, as shown.

ANGUS D. BAIN.
